UNITED STATES PATENT OFFICE.

THADDEUS C. JOY, OF TITUSVILLE, PENNSYLVANIA, ASSIGNOR TO T. C. JOY & CO., OF SAME PLACE.

DESIGN FOR A RADIATOR.

SPECIFICATION forming part of Design No. 20,471, dated January 6, 1891.

Application filed December 8, 1890. Serial No. 373,964. Term of patent 7 years.

To all whom it may concern:

Be it known that I, THADDEUS C. JOY, a citizen of the United States, residing at Titusville, in the county of Crawford and State of Pennsylvania, have invented and produced a new and original Design for Steam or Hot-Water Radiator-Sections, of which the following is a specification, reference being had to the accompanying drawings, forming a part thereof.

My design relates to hollow fluted sections of steam or hot-water radiators; and the leading feature of my design consists in a crowning arch-shaped termination for said sections, the said crowning termination being in cross-section of a form approximating or resembling the letter A, and the same forming an inclined continuation of the ribs forming the flutes of the sections, as illustrated in the accompanying drawings, in which—

Figure 1 is a side elevation of a radiator-section, showing my design; Fig. 2, an end view of two of the sections as placed side by side, showing my design; Fig. 3, a top view of a section, showing my design; Fig. 4, a horizontal section showing the type of hollow radiator-section on which my design is employed. Fig. 5 is an outline of an equivalent shape of the crowning, arched, and beveled termination shown in Figs. 1, 2, and 3; and Fig. 6, an outline showing another equivalent shape of the crowning, arched termination of the section shown in Figs. 1, 2, and 3.

A designates the ribs, which may be hollow or solid, and B spaces between the ribs of the fluted columnar sections; C, the beveled columnar ends.

D is the crowning, beveled, and arched terminations of the sections, the bevels thereof on each side extending from the ridge-bead *a* of a section to the outer edges of the ribs A, as shown in the drawings. The bead *a* at the center of a section and extending up from the base thereof to and over the arching termination may or may not be provided.

This design gives a highly ornamental and symmetrical finish to the top portions of the respective fluted radiator-sections represented, and when such sections are set up so as to constitute a given-sized radiator a tasteful effect is produced, no top to give a finish being required. Any tasteful or desirable additional ornamentation may be applied to the surface of the ornamentally-formed crowning arched terminations of the sections—such, for instance, as ornamental leaves or geometrical embellishing figures; but, while this is the ease, my design specially has reference to the crowning, arched, and beveled terminations of the fluted sections, as represented in the drawings.

What I claim as my invention is—

The design for radiator-sections, comprising fluted side surfaces and the crowning, arched, and beveled terminations, as herein described, and shown in the accompanying drawings.

In testimony whereof I hereunto affix my signature in presence of two witnesses.

THADDEUS C. JOY.
